UNITED STATES PATENT OFFICE.

CHARLES W. WYMAN, OF CLAREMONT, NEW HAMPSHIRE, ASSIGNOR TO SULLIVAN MACHINERY COMPANY, A CORPORATION OF MASSACHUSETTS.

CONTROLLING APPARATUS.

Application filed November 26, 1926. Serial No. 150,850.

This invention relates to controlling apparatus, and more particularly to electric controlling apparatus for use in connection with mining machines.

5 An object of this invention is to provide an improved controlling apparatus. Another object of this invention is to provide an improved electric controlling apparatus for a coal mining machine of the so-called long-
10 wall type. Still another object of this invention is to provide an improved interlocking mechanism disposed between the electric controlling mechanism and the conductor cable connector plug. Still another object
15 of this invention is to provide an improved controlling mechanism permitting operation of the motor controlled thereby in opposite directions while preventing the reversal of the motor except after the parts of the controlling mechanism have been returned to a predetermined position and a controller member therefor has been manipulated in a predetermined manner. Yet another object of this invention is to provide an improved
20 controlling mechanism provided with improved means for preventing movement of the controller handle to effect operation of the motor in a direction not desired. Still another object of this invention is to provide improved means for controlling an electric mining machine motor having an interlock with the current supply connector plug whereby the latter cannot be inserted or withdrawn except when the controller is locked
25 in its inoperative position. Another object is to provide improved operating connections for the controller. These and other objects and advantages of the invention will, however, hereinafter more fully appear.

30 In the accompanying drawings there is shown for purposes of illustration one form which the invention may assume in practice.

In these drawings,—

Fig. 1 is a plan view of a mining machine
45 of the longwall type within which my improved mechanism is embodied, the machine being disposed in operative position adjacent a working face.

Fig. 2 is a fragmentary end elevation view, partially in section, of the controlling end of the machine shown in Fig. 1.

Fig. 3 is a longitudinally extending vertical sectional view taken substantially on line 3—3 of Fig. 1.

55 Fig. 4 is a detail sectional view taken sub-

stantially on line 4—4 of Fig. 2 and illustrating the connector plug and the improved interlocking mechanism.

Figs. 5 and 6 are detail views of a portion of the improved controller and connector plug interlock, Fig. 5 being a section taken on line 5—5 of Fig. 4.

In this illustrative form of the invention the improved controlling apparatus and interlock mechanism are arranged within a mining machine generally designated 1, herein of the flexibly fed invertible type generally similar to that disclosed in a co-pending application to one Morris P. Holmes, Ser. No. 136,466, filed Sep. 20, 1926, and comprising a main frame 2 slideable on its bottom on the mine bottom. The main frame 2 comprises a cutter carrying section 3, a motor section 4, and a feed section 5, the cutter carrying section 3 and the feed section 5 being disposed at opposite ends of the motor section 4 and rigidly connected thereto in any suitable manner. A cutter bar 6 provided with an endless cutter bit carrying cutter chain 7 running around its margin is pivotally mounted on the frame section 3 on a vertical axis indicated at 8 and the cutter chain 7 is driven from the electric driving motor 9 which may be of either the AC or DC type housed within the frame section 4. Feeding movement of the machine relative to the working face is accomplished by means of a feed operating member 10, herein in the form of a chain sprocket, rotatable on a vertical axis and which is adapted to act on a flexible feeding member 11, herein in the form of a feed chain, having its outer free end fixed to a stationary extraneous abutment, not shown, in advance of the machine in a well known manner. The feeding mechanism is adapted to be controlled by a suitable handle 12 conveniently located at the forward end of the machine.

In the improved construction it will be observed that the motor section 4 has formed therein a chamber or compartment 13 in which is housed a controlling apparatus 14, as shown in Figs. 1 and 3 and including a usual controller drum horizontally disposed on an axis extending longitudinally of the machine and having a drum shaft 15. The controller is herein of the reversible rotary drum type substantially similar to that described and claimed in my co-pending appli- 110

cation Ser. No. 517,621, filed Nov. 25, 1921, and this controller is adapted to control the various electric circuits to the driving motor 9. As the controller per se does not form part of my present invention it will not be described specifically herein. As illustrated, the shaft 15 of the controller drum has fixed thereto as by a screw 16 an enlarged hub 17 and this hub is provided with a squared opening 18 adapted to slidably receive the squared end 19 of a horizontal shaft 20 alined with the drum shaft 15 and journaled in a bearing 21 formed within the frame section 4. As clearly shown in Fig. 3 the forward end of the shaft 20 has formed integral therewith a socket portion 22 having a squared opening 23 which loosely receives the squared end 24 of an angularly disposed control bar 25. The forward end of the control bar 25 is squared as at 26 and is loosely received in a squared opening 27 formed within a socket portion 28 carried by the rear end of a control shaft 29 arranged parallel with the shaft 20, the shaft 29 being rotatably mounted in a bearing or bracket 30 secured as by screws 31 to the frame section 5. The squared ends 24, 26 of the control bar 25 and the cooperating squared recesses 23, 27 form a universal or flexible connection between the shafts 20 and 29. Communicating with the squared opening 27 and extending forwardly within the shaft 29 is a recess 32 in which a coiled spring 33 is disposed. The spring 33 reacts between the shaft 29 and the adjacent end of the control bar 25 and consequently maintains the parts 29, 25, and 22 in operative relation. As clearly shown in Fig. 3 the control bar 25 extends through a chamber 34 formed within the frame section 5. In accordance with this illustrative embodiment of the invention the shaft 29 is provided with a forwardly projecting reduced portion 35 which has keyed thereto at 36 and slidably axially thereon an operating handle 37. The controller handle 37 is arranged at the opposite side of the machine from the feed control handle 12. The hub portion of the handle 37 is provided on its periphery with a longitudinally extending slot 38 whose opposite ends open into oppositely circumferentially extending peripheral slots 39 and 40. A depending portion or lug 41 preferably formed integral with the bearing member 30 extends into the groove made up by the slots 38, 39 and 40 and when this lug 41 is in the position shown in Fig. 6 the handle 37 may be rotated in only one direction, but when the handle 37 is slid outwardly to the position shown in Fig. 3 the handle 37 may be rotated in only the opposite direction. It will herein be observed that the shaft 29 is provided with a flattened or cut way portion 42 which is engaged when in a predetermined position by a plunger or locking pin 43 slidably mounted at 44 in a connector plug casing 45 secured to the machine frame. The locking pin 43 is normally resiliently maintained in engagement with the shaft 29 by means of a coiled spring 46 acting between the plug casing 45 and a washer 47 pinned to the plunger. Also formed in the plug casing 45 is a horizontally disposed bore 48 extending longitudinally of the machine frame and receivable in this bore is a detachable power supply connector plug 49 to which a conductor cable 50 is suitably connected. The conductor plug 49 is of well known form and need not be specifically described herein. As clearly shown in Fig. 4 the cylindrical casing 51 of the connector plug 49 has formed therein a recess 52 adapted to receive the inner end of the locking pin 43 as will later be described.

As heretofore described the lug 41 may project within the longitudinal slot 38 formed within the controller handle 37 and when such relation exists the controller drum is disposed in its inoperative or neutral position. At this time the flattened surface 42 on the shaft 29 is in a position to receive the locking pin 43, the spring 46 maintaining the pin therein and released from the locking aperture 52 in the connector plug 49. It is obvious that the connector plug 49 can be removed longitudinally from the bore 48 at that time. If it is desired to rotate the controller drum in one direction or the other the operator must grasp the handle 37 and slide the same longitudinally either inwardly or outwardly along the shaft 29 until the lug 41 is disposed in alignment with one or the other of the circumferentially extending slots 39 and 40. The controller handle 37 can thus be rotated and upon rotation thereof the flattened surface 42 acts as a cam and forces the locking pin 43 therefrom and into engagement with the locking recess 52 in the connector plug, thereby locking the latter against removal until the controller handle is again brought into its neutral or inoperative position. It will also be observed that if the controller is rotated into operative position while the connector plug 49 is removed the locking pin 43 prevents the insertion of the plug within the bore 48 until the controller drum is again returned to its neutral or inoperative position.

As a result of this invention it will herein be noted that an improved controlling apparatus for a mining machine is provided having improved interlocking means between the power supply connector plug and the controller drum wherein the latter must be in its neutral or inoperative position prior to the removal of the connector plug and wherein the supply connector plug is locked in position during operation of the controller, consequently preventing arcing and

resultant disastrous explosions due to inadvertent release of the plug while the controller is on. These and other advantages of this invention will be clearly apparent 5 to those skilled in this art.

While I have in this application specifically described one form which my invention may assume in practice, it will be understood that this form of the same is shown for 10 purposes of illustration and that the invention may be modified and embodied in various other forms without departing from its spirit or the scope of the appended 15 claims.

What I claim as new and desire to secure by Letters Patent is:

1. In an electric controlling mechanism, a controller including a shaft movable in opposite directions from a given position to 20 produce different circuits, and means including a grasping handle mounted on said shaft for moving said controller, said handle being adjustable relative to said shaft to selectively control the direction in which said controller may be moved from said position.

2. In an electric controlling mechanism, a controller including a shaft movable in opposite directions from a given position to produce different circuits, and means including a rotatable handle slidably mounted 30 on said shaft for moving said controller, said handle being slidable relative to said shaft to selectively control the direction in which said controller may be moved from said position.

3. In an electric controlling mechanism, a controller including a rotatable shaft adapted on rotation in opposite directions from a given position to produce different circuits, and means including an operating handle 40 for rotating said shaft and reciprocable rectilinearly thereon for selectively controlling the direction in which said shaft may be rotated from said position.

4. In an electric controlling mechanism, a controller including a shaft mounted only for rotation on a fixed axis and adapted on rotation in opposite directions from a given position to produce different circuits, and 50 means including a grasping handle on said shaft reciprocable coaxially with and relative to said shaft for selectively controlling the direction in which said shaft may be rotated from said position.

5. In an electric controlling mechanism, a controller including a rotatable shaft fixed against longitudinal movement and adapted on rotation in opposite directions from a given position to produce different circuits, and means including a rotatable grasping handle reciprocable rectilinearly in a line parallel to a line parallel to said shaft for selectively controlling the direction in which said shaft may be rotated from said position.

6. In an electric controlling mechanism, a

controller including a rotatable shaft fixed against longitudinal movement and adapted on rotation in opposite directions from a given position to produce different circuits, means including a grasping handle rotatable 70 with said shaft and having a plurality of longitudinally offset oppositely extending peripheral grooves, and a stationary element engaging in said grooves for controlling the direction in which said grasping handle may 75 be rotated from said position.

7. In an electric controlling mechanism, a controller including a shaft mounted only for rotation on a fixed axis and adapted on rotation in opposite directions from a given 80 position to produce different circuits, means including a grasping handle rotatable with said rotatable shaft and reciprocable relative thereto longitudinally thereof, and a stationary abutment member for controlling the direction in which said grasping handle may 85 be rotated from said position.

8. In an electric controlling mechanism, a rotatable member, means for controlling the direction of rotation of said member includ- 90 ing an operating handle member rotatable therewith and having a pair of spaced oppositely extending grooves therein connected by a groove extending longitudinally of said handle, and a member extending into said 95 groove, one of said members being movable relative to the other to control the direction of rotation of said first mentioned member.

9. In an electric controlling mechanism, a rotatable member, means for controlling 100 the direction of rotation of said member including a grasping handle member rotatable therewith and having a pair of spaced oppositely extending grooves therein connected by a groove extending longitudinally of said handle, and a member extending into said 105 groove, said handle member being movable oppositely longitudinally to effect control of the movement of said first mentioned member.

10. In an electric controlling mechanism, a controller including an operating shaft, a handle mounted thereon, said handle being slidable longitudinally on said shaft, means cooperating therewith on slidable movement for selectively controlling the direction in which said shaft may be rotated, said shaft having a cam surface thereon, a connector plug, and means including a slidable locking member cooperating with said cam surface for interlocking said controller with said plug.

11. In an electric controlling mechanism, a controller rotatable in opposite directions from a given position to produce different circuits, operating means for said controller including parallel shafts and an angularly disposed control bar connecting said shafts, and means including an operating handle 125 for said controller reciprocable rectilinearly 130

upon one of said shafts for selectively controlling the direction in which said controller may be rotated.

12. In an electric controlling mechanism, 5 a controller rotatable in opposite directions from the given position to produce different circuits, operating means for said controller comprising parallel shafts each having a squared recess therein, an angularly disposed 10 control bar having squared ends receivable in said recesses for connecting said shafts, and means including an operating handle for said controller reciprocable rectilinearly upon one of said shafts for selectively controlling the direction in which 15 said controller may be rotated.
13. In an electric controlling mechanism, a controller rotatable in opposite directions from a given position to produce different 20 circuits, operating means therefor including parallel shafts, an angularly disposed control bar connecting said shafts, a handle slidably mounted on one of said shafts, means cooperating with said handle for selectively controlling the direction in which 25 said controller may be rotated, a connector plug, and means cooperating with one of said shafts for interlocking said connector plug with said controller.
14. In an electric controlling mechanism, 30 a controller rotatable in opposite directions from a given position to produce different circuits, operating means therefor comprising parallel shafts each having a squared recess, an angularly disposed control bar

having squared ends receivable in said recesses for connecting said shafts, an operating handle slidably mounted on one of said shafts, means cooperating with said handle for selectively controlling the direction in 40 which said controller may be rotated, a connector plug, and means cooperating with one of said shafts for interlocking said connector plug with said controller.

15. In combination with a reversible controller for a reversible motor, an operating shaft for said controller, a handle slidably and non-rotatively mounted thereon, and a stationary member cooperating with said handle to prevent reversal of said controller 50 until said handle has been slidably moved on said shaft a predetermined amount in neutral position.

16. In combination with a reversible controller for a reversible motor, an operating shaft for said controller, a handle slidably and non-rotatively mounted thereon, a stationary member cooperating with said handle to prevent reversal of said controller until 55 said handle has been slidably moved on said shaft a predetermined amount in neutral position, a connector plug through which current is supplied to said controller, and mechanical interlocking means between 60 said shaft and plug preventing withdrawal 65 or insertion of said plug when the controller is in any of its on positions.

In testimony wherof I affix my signature.

CHARLES W. WYMAN.
